UNITED STATES PATENT OFFICE.

KATHERINE B. FULD, OF BALTIMORE, MARYLAND.

TOY.

1,329,338.

Specification of Letters Patent.

Patented Jan. 27, 1920.

Application filed August 21, 1919. Serial No. 318,855.

To all whom it may concern:

Be it known that I, KATHERINE B. FULD, a citizen of the United States, residing at Baltimore, State of Maryland, have invented 5 certain new and useful Improvements in Toys, of which the following is a specification.

This invention relates to toys and more particularly to that class of such devices 10 known to the art as figure toys, and has for its object the provision of a device of the character described adapted to represent the distinctive movement of a certain animate object, as a jumping frog or the like, mechanism being provided whereby such movement is attained to produce a pleasing and amusing novelty.

Reference being had to the accompanying drawings forming a portion of this 20 specification, and in which is illustrated an embodiment of the invention, like characters being used to indicate like parts as they occur,

Figure 1 is a side elevation partly broken 25 away and showing some of the positions assumed by the device;

Fig. 2 is a side elevation of the device in normal position, and

Fig. 3 is a detail section on line 3—3 of 30 Fig. 2.

The toy figure comprising a body portion 4, decorated to represent a frog or other suitable animal is mounted upon a platform 5 having a centrally disposed slot 6 and 35 carried by axle supports 7—8 carrying pairs of wheels 9—10 on axles 11—12, the rear axle 12 being bent to form a crank 13 to which is pivoted a link 14 connected at 15 to the rear under portion of the body 4.

40 The front end of the body 4 has a pair of fore legs 16 rigidly secured thereto at 17 and pivotally mounted at 18 in slots 19 formed in the foot portion 20 fixed to the platform 5.

45 Pivoted at 21 to the rear of the body 4 are legs comprising an upper member 22 to which is pivoted at 23 a lower member 24 normally resting in horizontal position on the platform 4 as shown in Fig. 2.

50 Means 25 are provided to assist in propelling the device.

The device described operates in the following manner:

As the device is moved in a forward or rearward direction the axle 12 is rotated by its pair of wheels 10 reciprocating the link 14 carried by the crank portion 13, thus raising and lowering the figure, which is also given a forward and rearward movement about the pivots 18, the fore legs 16 being fast to the body portion 4 at 17. The rear legs being free to move on pivots 21 and 23 assume, during the operation of the device, a great number of varied positions of both the upper member 22 and the lower member 24, which may be accentuated by the speed of propulsion and which effectively present an imitation of a jumping frog.

I realize that considerable variation is 70 possible in the details of construction and arrangement of parts without departing from the spirit of my invention, and I therefore do not intend to limit myself to the specific form shown and described.

I claim:

1. In a toy, in combination, a wheel supported platform, a body portion of a figure, a pair of foot members secured to said platform and having slots therein, a pair of fore leg members pivoted to the foot members in said slots and fast on the body portion, a pair of rear leg members pivoted to the body portion and free of said platform, said rear legs comprising an upper member 80 on the body portion and a lower member pivoted to the upper member.

2. In a toy, in combination, a wheel supported platform, a body portion of a figure, a pair of foot members secured to said platform and having slots therein, a pair of fore leg members pivoted to the foot members in said slots and fast on the body portion, a pair of rear leg members pivoted to the body portion and free of said platform, 90 said legs comprising an upper member on the body portion and a lower member pivoted to the upper member, and means for reciprocating said body portion.

3. In a toy, in combination, a wheel supported platform, a body portion of a figure, a pair of foot members secured to said plat-

form and having slots therein a pair of fore leg members pivoted to the foot members in said slots and fast on the body portion, a pair of rear leg members pivoted to the body portion and free of said platform, said legs comprising an upper member on the body portion and a lower member pivoted to the upper member, means for reciprocating said body portion, said means com-

prising a crank axle and a link between said axle and the body portion of said figure.

In testimony whereof I affix my signature in presence of two witnesses.

KATHERINE B. FULD.
